PUMP CONSTRUCTION

Andre de Weal, Franz K. Krag, and Charles A. Anderson, Chicago, Ill.; said Krag and said Anderson assignors to said de Weal

Application January 19, 1934, Serial No. 707,330

2 Claims. (Cl. 221—103)

This invention relates to a new and improved pump construction, and more particularly to such a construction adapted for use in atomizers, sprayers, and the like.

5 In the design and manufacture of pumps for such purposes it is essential to provide a device which is simple and effective in operation, and which may be locked or closed so as to prevent accidental losses of fluid or losses by evaporation.

10 Pumps and sprayers or atomizers of this character are generally used in connection with somewhat volatile liquids such as perfumes, lacquers, insecticides, glass cleaning solutions or other like materials. With such fluids the pump 15 and closures must be designed with closely fitting parts, and with parts not subject to corrosion by the material being handled.

Devices of this character also must be low in manufacturing cost, as in many cases the liquids are sold in containers with the sprayer 20 attached, and the sprayer is used merely to spray the contents of the container and then thrown away with the container. In many cases it is desirable to ship the container with the pump 25 and sprayer in place in the container, both to save shipping space and to avoid the cost of an extra closure member. In such cases it is highly important to provide locking means to prevent operation of the sprayer by the handling of the 30 package in transport, when, for example, the package is handled upside down. This is important to prevent leakage and loss of the fluid, and also to prevent discoloring of the carton or container in such manner as to render it unsightly and hence not readily salable. For these 35 reasons it is also important to prevent any seepage of the material due to loose fitting parts of the device.

The locking means should be simple in design 40 to reduce cost, and also easy of operation to insure it being used. The locking device should be readily locked and unlocked by the user of the pump or sprayer so that it will normally be locked after use. This will prevent losses due 45 to evaporation, and also in case the receptacle is accidentally knocked over.

It is an object of the present invention to provide a new and improved pump and sprayer or atomizer construction.

50 It is a further object to provide a construction of this character in which means are provided for locking the pump in fixed position.

It is also an object to provide a construction 55 in which, when locked in fixed position, means

are provided for preventing leakage through or around the pump parts.

It is an additional object to provide a pump construction composed of but few and simple parts, and adapted for commercial production. 5

Other and further objects will appear as the description proceeds.

We have shown certain preferred embodiments of our invention in the accompanying 10 drawing in which—

Figure 1 is a vertical section showing one form of pump;

Figure 2 is a vertical section showing a modified form of pump;

Figure 3 is a plan view of the construction 15 shown in Figure 2;

Figure 4 is a vertical section of an additional modified form of pump;

Figure 5 is a section taken on line 11—11 of 20 Figure 4;

Figure 6 is a fragmentary section taken on line 12—12 of Figure 5; and

Figure 7 is a fragmentary plan view on a reduced scale of the valve member of Figure 4. 25

Referring first to the form of construction shown in Figure 1, the receptacle 71 is provided with a closure member 72, which closure member has a central opening through which passes the hollow piston rod 73, this rod having the angularly extending upper portion 74. This 30 portion 74 carries the nozzle 75 with discharge opening 76, and atomizing device 77, which in this form is cup shaped. The base member 78 and finger piece 83 are secured to the hollow piston rod 73. The cylinder 79 is located within 35 the receptacle and has its upper edge 80 crimped through the opening in the closure member to secure the cylinder in place, and also to retain in place the guide member 81. This guide member is formed with the notch 82 in which the 40 angularly extending portion 74 of the hollow piston rod may be reciprocated. When this portion of the piston rod 73 is in the plane of the section of Figure 1, it reciprocates freely in the notch 82, but this portion locks the pump 45 by engaging the top of the guide member 81 when the finger piece and nozzle are turned about the axis of the piston rod for any appreciable angle.

The hollow piston rod 73 has a lower reduced 50 portion 85 upon which is slidably fitted the piston 86 which has the downwardly depending skirt 87 closely fitting the inner walls 79. The upper face of the piston 86 carries a packing ring 88 which serves to seal the opening in the 55

upper end of the cylinder when the piston is drawn to its upward limit of movement. The lower end of the hollow piston rod 73 is closed by the member 89 which has the upwardly extending portion 90 spaced from the piston rod. The circular flange 91 is secured on the piston rod at a point between the piston 86 and the member 89.

The lateral opening 92 is formed in the hollow piston rod at a point between the flange 91 and member 89. The lower side of the piston 86 carries a packing 93 which in the lower position of the piston 86 engages the flange 91 and the upwardly extending flange portion 90 of the member 89 so as to seal the opening 92. The compression spring 94 engages the member 89 and at its opposite end rests on the spider 95, which in turn is carried by the bottom 96 of the cylinder 79.

The intake pipe 97 extends from the bottom 96, and the ball valve 98 which is retained in place by the spider 95 serves to close the intake opening 97 when in its lower position. The upper portion of the cylinder 79 above the piston 86 is provided with the relief opening 99 which is in communication with the interior of the receptacle.

Referring next to the form of construction shown in Figure 2, the closure member supporting the pump construction is shown at 101. In this form of construction the pump is provided with two directly connected cylinders, and the discharge passage remains fixed in position during the pumping operation. The upper cylinder member 102 has its upper edge crimped over an opening in the closure member at 103, this crimped portion also retaining in place the guide member 104 which is tubular in form with a cover member 104'. The upper wall of the cylinder member 102 is provided with the relief opening 105.

The hollow piston rod 106 passes through the opening into the upper cylinder 102. The finger piece 107 is secured to the upper end of the rod 106 by the rivet 108. The guide member top 104' is provided with the arcuate opening 109 through which the outer end of the rivet 108 passes when the finger piece 107 is turned to the position shown in Figure 2 in operating the pump. The outer end of the rivet 108 rests on the top 104' of the guide member when the finger piece 107 is turned to the dotted line position of Figure 2 to lock the pump.

The upper cylinder piston 110 is fixedly secured between the hollow pump rod 106 and the lower pump rod 111. The piston 110 carries the packing 112 upon its upper face, the packing serving to close the opening about the rod 106 when the parts are locked in the upper position. It is necessary to have a moderate amount of play about the rod 106 as it passes through the closure so as to permit entrance of air at this point during the operation of the pump. The pump is double acting, and unless sufficient air is permitted to enter at this point a vacuum will build up in the receptacle during the pumping operation.

The lower portion 113 of the cylinder 102 is enlarged and is secured to an upper enlarged portion 114 of the lower cylinder 115. These enlarged portions of the cylinders form a connecting valve and discharge chamber 116 for the two cylinders. In this chamber is fitted the valve plate 117 which carries the pin 118 and the packing member 119. The pin 118 extends into the lower end of the discharge tube 120 and thus

maintains the valve in proper position. This tube passes through the closure member 101 and is joined to the angularly extending tube 121 which carries the discharge nozzle 122 with the member 123 therein to assist in the atomization. 5

The spring 124 has its upper end engaging the lower side of the piston 110 and its lower end resting upon the valve plate 117. The lower portion of the lower pump rod 111 is reduced in size and carries the piston 125 slidably fitted thereon. The lower end of the rod 111 is closed by the member 126 which has the upwardly directed circular flange 127. The lower side of the piston 125 carries the packing 128 adapted to engage the flange 127 when the piston is at its lower limit of movement on the rod 111. The rod 111 is hollow and is provided with the inlet opening 129 located between the member 126 and piston 125. It is provided with the outlet opening 130 at a point above the piston 125. The downwardly extending skirt of the piston 125 may be split as indicated at 131 so that the skirt may engage the inner cylinder walls with sufficient friction to insure the piston being retarded so that the packing 128 engages the flange 127 25 promptly during the upstroke of the piston.

The suction pipe 132 leads from the bottom of the lower cylinder 115. The ball valve 133 is held adjacent the upper end of the pipe 132 by the spider 134 held in place by the spring 135. The upper end of spring 135 engages the lower side of the member 126.

The form of construction shown in Figure 4 is generally similar to the upper portion of the form shown in Figure 2. The closure member or receptacle wall 140 carries the cylinder 141 and the discharge passage 142. The pipe 143 connects the passage 142 to the enlarged lower portion 144 of the cylinder 141. The piston rod 145 is provided with the finger piece 146 held on by rivet 147, the head of which coacts with the cam 148 carried by the locking member 149. The lower end of the rod 145 carries the piston 150 having the packing 151 on its upper face. The spring 152 engages the under side of the piston 150 and the upper side of the valve member 155. The valve member carries the locating pin 154 and the packing washer 153. The valve lift rod 156 extends downwardly from the piston rod 145 and carries the enlargement 157 adapted to engage the valve member 153 to lift and close the valve when the piston rod is locked in its upper position. The cylinder 141 is provided with the relief opening 158 formed in its upper side wall. 45

The form of construction shown in Figure 1 is locked when the lower edge of the angular portion 74 of the pump rod rests on the upper edge of the guide member 81. With the parts in this position the packing 88 is urged against the cylinder top and prevents leakage around the piston rod 73. The packing 93 is also urged against both the flanges 90 and 91. This serves not only to seal the opening 92 against fluid in the pump cylinder, but also against any leakage of air between the piston 86 and the pump rod 85. This seals the lower end of the pump rod against atmospheric relief and prevents loss of fluid either from the cylinder or that contained in the pump rod itself. 60

To operate the pump, the pump rod portion 74 is turned until it will pass into the notch 82, the base member 78 and finger piece 83 passing down inside the guide member 81 when depressed. Pressure on the finger piece then forces the hollow piston rod 73 and the member 89 downwardly against the resistance of spring 94. As this move- 70 75

ment starts, the frictional engagement of the skirt 87 of the piston 86 and the fluid in the cylinder retard movement of the piston so that the packing 93 clears the two flanges 90 and 91. Any fluid in the cylinder at this time is trapped by the ball valve 98 and is forced through the opening 92 into the hollow piston rod 73 and up and out through the nozzle orifice 76.

After the down stroke is completed, pressure on the finger piece is released and the piston assembly is raised by the spring 94. Air in the cylinder above the piston passes into the receptacle through the orifice 99. As the piston assembly moves upwardly the piston is retarded until the packing 93 engages the flanges 90 and 91, closing the port 92. The upward movement of the piston creates a suction in the cylinder, and fluid is drawn up pipe 97 past valve 98 into the cylinder. These actions of the parts are repeated upon continued reciprocation of the piston assembly, and fluid is discharged upon each down stroke of the piston. After the desired use has been had of the device it may be locked by turning the finger piece until the portion 74 again rests on the member 81.

The operation of the form of construction shown in Figures 2 and 3 differs from those previously described in that the discharge nozzle remains stationary during the operation of the pump. A further difference lies in the fact that the pump is provided with two cylinders so connected as to discharge alternately so that flow from the nozzle occurs both upon the up and down strokes of the piston rod, and is therefore substantially continuous.

When the pump is locked, the finger piece 107 is turned to the left as seen in Figure 2, and the head of rivet 108 rests on the top surface 104'. The packing 112 seals the opening about the piston rod 106, which opening is made large enough to permit entrance of air about the piston rod during operation, as otherwise an undesirable partial vacuum might be created in the receptacle due to the double acting pump. The lower piston 125 engages the valve member 117 and closes the valve packing 119 against the opening into tube 120 so as to prevent discharge of fluid. The engagement of the piston 125 with the valve member forces the piston downwardly until the packing 128 engages the flange 127, thus sealing the inlet opening 129.

To operate the pump, the finger piece 107 is turned to the position in which it is shown in full lines in Figure 2. The spring 124 forces down the valve member 117 and opens the discharge valve. As the finger piece is pressed downwardly, the piston 110 moves downwardly, forcing fluid in the upper cylinder 102 out through the discharge tube 120. The fluid cannot move down into the lower cylinder 115 as the lower piston 125 goes down, as fluid is passing through that piston. As the lower piston moves downwardly, fluid below the piston is trapped by valve 133 and passes through orifice 129 into the hollow pump rod 111 and then out through the opening 130 above the piston. Thus the fluid displaced by the upper piston must pass out the discharge tube.

When the downward stroke is completed, the finger piece is released and the springs 124 and 135 force the piston assembly upwardly. Air trapped above the upper piston passes out through opening 105 into the receptacle. As the upward movement starts, the piston 125 is re-

tarded by its frictional contact with the cylinder walls and the packing 128 engages flange 127, thus preventing the liquid above the piston from passing downwardly through the piston. Liquid above the piston is thus forced upwardly. Part 5 of its enters the upper cylinder 102, but as that cylinder has only half the capacity of the lower cylinder, half of the fluid is forced out through the discharge tube 120.

The form of construction shown in Figures 4, 10 5, 6 and 7 is operated in a manner similar to the construction of Figures 2 and 3, with the exception that it has a single cylinder and consequently is single acting and discharges only on the downward stroke of the single piston. 15 The sealing devices are the same as far as the top of the cylinder is concerned. When the pump is locked with rivet head on the cam 148 the enlargement 157 on the valve lift rod 156 engages the valve member 155 and forces the packing 153 against the lower end of the discharge tube, sealing that tube. It will be understood that the lower end of the suction tube in Figure 4 will be provided with any usual type of 20 check valve.

An important feature of the cup 71 of Figure 1 or the member 123 of Figure 2 lies in the fact that these elements have a double function. They are loosely fitted in the nozzle and are primarily designed to aid in the formation 30 of a proper spray from the nozzle. They will also, however, function as check valves seating against the end of the tubular piston rod on the upstroke of the piston to prevent entrance of air through the nozzle, and thus make for 35 greater efficiency in the suction stroke.

While we have shown and described certain preferred forms of our invention, these are to be understood to be illustrative only, as it is capable of further modification to meet varying 40 conditions and requirements, and we contemplate such changes and variations as come within the spirit and scope of the appended claims.

What is claimed is:

1. In a pump construction, a closure member 45 having an opening therein, a pump rod extending through the opening, a cylinder secured to the closure member below the opening, a piston on the pump rod in the cylinder, a packing on the upper face of the piston adapted to seal the opening in the closure member with the piston in its upper position, and means for locking the piston in its upper position.

2. In a pump construction, a closure member 55 having an opening therein, a hollow pump rod having an operating portion extending through the opening, a closure for the lower end of the pump rod, the pump rod having a lateral intake opening formed in its lower portion and a discharge opening formed in its upper portion, a cylinder located below the closure member, a floating piston on the pump rod in the cylinder, said piston serving as a valve to open and close the intake opening on the pump rod, a packing carried by the upper face of the floating piston, 60 and means to lock the pump rod at its upper limit of movement with the packing engaging the under side of the closure member and thus sealing the opening in said member about the pump rod.
